(57) **CLAIM**

We claim the ornamental design for a dynamic keypad for controlling electrical loads, as shown and described.

DESCRIPTION

FIG. 1 is a perspective view of a dynamic keypad for controlling electrical loads according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a dynamic keypad for controlling electrical loads according to a second embodiment of our new design.

FIG. 8 is a front view thereof.

FIG. 9 is a left side view thereof.

FIG. 10 is a right side view thereof.

FIG. 11 is a top view thereof.

FIG. 12 is a bottom view thereof.

FIG. 13 is a perspective view of a dynamic keypad for controlling electrical loads according to a third embodiment of our new design.

FIG. 14 is a front view thereof.

FIG. 15 is a left side view thereof.

FIG. 16 is a right side view thereof.

FIG. 17 is a top view thereof; and,

FIG. 18 is a bottom view thereof.

The rear views form no part of the design and are omitted.
